UNITED STATES PATENT OFFICE.

RUDOLPH F. STEHLIK, OF CHICAGO, ILLINOIS, ASSIGNEE, BY MESNE ASSIGNMENTS,
TO AUTOMATIC ELECTRIC INC., OF CHICAGO, ILLINOIS, A CORPORATION OF DELA-
WARE.

TELEPHONE SYSTEM.

Application filed December 23, 1922. Serial No. 602,764.

The present invention relates to telephone systems in general, but is concerned more particularly with telephone systems in which finders are employed; and the principal object, broadly stated, is the production of a finder system which is reliable in operation and simple in construction.

More specifically, an object of the invention is the production of suitable circuit arrangements whereby a signal is given to an attendant whenever there is trouble with the starting circuit when a subscriber attempts to initiate a call.

Another feature of the invention relates to the provision of circuit arrangements such that the usual starting or line relay and the test relay usually found in each finder are replaced by a single holding relay in each finder, and one line relay and one test relay are placed in the common allotter and take care of the starting and testing operations of all the finders.

Referring now to the drawings comprising Figs. 1 and 2, they show by means of the usual circuit diagrams a sufficient amount of apparatus in a system embodying the principles of the invention to enable the invention to be thoroughly understood.

Figure 1 shows the substation A of which the line terminates at the exchange in the banks of a group of finders such as the finder F, and has associated with it the line circuit LC. This drawing shows also the relay group RG which contains the necessary starting and signal relays and operates in conjunction with the finder allotter FA for starting an idle finder when a call is made.

Figure 2 shows a connector C, which is individual to the finder F, and also a subscriber's line which is accessible to the connector C and with which is associated the line circuit LC'.

The finders such as F and the finder allotter FA are mechanically of the well-known rotary type of switch of which the wipers have no normal position, and are advanced in a forward direction only by the stepping magnet, and of which the wipers are advanced when the stepping magnet de-energizes rather than when the stepping magnet energizes.

The connector C, Fig. 2, is an automatic switch of the usual vertical and rotary type and, accordingly, its bank contacts are arranged in horizontal rows or levels.

In order to explain the detailed operation of the equipment shown, it will be assumed that the subscriber at substation A desires to converse with the subscriber at substation A' and, accordingly, removes his receiver from the switch-hook.

When the receiver is removed at substation A, a circuit is closed over line conductors 11 and 12 for line relay 13 of the line circuit LC, line relay 13 being connected with conductor 11 through the resting contact of armature 18 and said armature, and conductor 12 being grounded through armature 21 and its resting contact. Upon energizing, line relay 13 disconnects test contact 27 from ground, and connects it to private normal conductor 22 at armature 15, thereby placing the circuit in readiness for the calling line to be made busy to the connectors having access to it, and for cut-off relay 14 to be energized when the calling line is found. As a further result of the energization of line relay 13, it opens a point in the chain circuit by means of which relay 42 is normally shunted at armature 16, and at armature 17 closes a circuit for relay 43. Relay 43 energizes in response to its circuit being closed at armature 17, and relay 42 energizes in response to the shunt being removed from around it at armature 16.

Upon energizing, relay 43 opens a point in the circuit of relay 45, and places ground on start conductor 99 at armature 50 by way of relay 44 and armature 59 and its resting contact. Relay 42, upon energizing, places a multiple ground on start wire 99. Relay 44 now energizes in series with line relay 82 of the finder allotter FA by way of the resting contact of armature 89 and said armature, and at armature 51 disconnects the lamp L' so as to prevent it from becoming lighted at this time.

Line relay 82 of the finder allotter FA, upon energizing over start conductor 99, closes at armature 86 a circuit for test relay 84, and stepping magnet 94 of the allotted finder F in series, by way of wiper 91 and the bank contact upon which it is standing, and at armature 85 connects test wiper 73 of the finder F to the junction of test relay 84 and stepping magnet 94 by way of wiper 92 and the bank contact upon which it is standing and the resting contact of armature 97 and said armature. In case the wipers of the finder F are standing upon the terminals

- of the called line, the connecting up of test wiper 73 does not have any effect and test relay 84 energizes immediately. Assuming, however, that the wipers of the finder F are not standing on the terminals of the calling line, but are standing on some other set of terminals, which is usually the case, test relay 84 is short-circuited by the grounded potential encountered by test wiper 73, and
- 10 the wipers of the finder F are rotated step by step by the buzzer-like action of stepping magnet 94 which is operated from the ground encountered on the busy test contacts.
- 15 When the terminals 26-28, inclusive, of the calling line are reached, test wiper 73 encounters the ungrounded contact 27, and test relay 84 in the finder allotter FA, being no longer short-circuited, energizes in series
- 20 with stepping magnet 94 of the finder F, stepping magnet 94 not energizing at this time on account of the high resistance of test relay 84. Upon energizing, test relay 84 closes at armature 87 a circuit for stepping magnet 81 which is exclusive of the local interrupter contacts of the stepping magnet. Stepping magnet 81, upon energizing, merely moves its pawl (not shown) into engagement with the next notch in the associated wiper driving ratchet wheel but does not advance the switch wipers. As a further result of the energization of test relay 84, it closes a circuit for cut-off relay 83 at armature 90. Relay 83, upon energizing, opens the circuit of line relay 82 at armature 89. Line relay 82, however, being slow-acting, does not fall back immediately.
- As a still further result of the energization of test relay 84, a circuit is closed for relay
- 40 95 of the finder F in multiple with relay 83 of the finder allotter FA as follows: From ground by way of the working contact of armature 90 and said armature, wiper 93 and the bank contact upon which it is standing, spring of key K and its resting contact, and relay 95 to battery. Upon energizing, relay 95 connects up the line wipers 72 and 74 at armatures 96 and 98, and at armature 97 disconnects test wiper 73 from the junction of
- 45 stepping magnet 94 and test relay 84 and connects it to ground, thereby closing a circuit for cut-off relay 14 through test wiper 73, test contact 27, and armature 15 of line relay 13 and its working contact. Upon energizing, cut-off relay 14 disconnects ground from the resting contact of armature 15 at armature 19 so as to prevent test contact 27 from becoming grounded locally when line relay 13 deenergizes subsequently;
- 50 closes a locking circuit for itself at armature 20; and at armatures 18 and 21 disconnects the winding of line relay 13 and ground from conductors 11 and 12, respectively. Line relay 13 now deenergizes; opens the circuit of start relay 43 at armature 17; and
- places a shunt around start relay 42 at armature 16, whereupon relays 42 and 43 deenergize and remove ground from start conductor 99 at armatures 49 and 50.
- In the connector C, line relay 102 energizes over the calling line in response to the line conductors being connected up in the finder F at armatures 96 and 98, and closes a circuit for release relay 103 at armature 116. Release relay 103, upon energizing, prepares the operating circuit at armature 119; prepares a circuit for switching relay 108 at armature 118; and at armature 117 places ground on release trunk conductor 76, thereby establishing a holding circuit for holding relay 95 before the slow-acting line relay 82 of the finder allotter FA has had time to deenergize.
- When line relay 82 of the finder allotter eventually deenergizes, it separates the wipers 91 and 92 at armature 85, and at armature 86 opens the circuit of test relay 84. Upon deenergizing, test relay 84 removes ground at one point from release trunk conductor 76 at armature 90, leaving relay 95 of the finder F and relay 83 of the allotter FA energized by ground sent back by the connector C over release trunk conductor 76. As a further result of the deenergization of test relay 84, it opens the circuit of stepping magnet 81 at armature 87, whereupon stepping magnet 81 deenergizes and advances the wipers 91-93, inclusive, into engagement with the next set of bank contacts.
- In case the finder associated with the next set of bank contacts is busy, relay 83 does not deenergize and the wipers 91-93, inclusive, do not stop there but are rotated step by step in search of an idle finder by the buzzer-like action of stepping magnet 81, which operates from ground picked up on the busy test contacts by test wiper 93. When an idle finder is finally reached, relay 83 deenergizes and connects up line relay 82 again at armature 89 so as to render line relay 82 operative for the next call.
- When the calling subscriber operates his calling device for the first digit in the desired number, the circuit of line relay 102 is opened a corresponding number of times at the calling substation, and each time line relay 102 deenergizes, it closes at its armature 116 a circuit for vertical magnet 110, the circuit at the time of the first closure being as follows: from ground by way of armature 116 and its resting contact, armature 119 and its working contact, contact of off-normal spring 113 and said spring, relay 104, and vertical magnet 110 to battery. By the operation of vertical magnet 110, the switch wipers 133-135, inclusive, are raised opposite the level of contacts in which the terminals of the desired line are located. Relay 104 is energized in series with vertical

magnet 110 and, being slow-acting, retains its armature attracted throughout the vertical movement, thereby maintaining its own circuit and that of vertical magnet 110 intact after the off-normal springs have shifted as they do upon the first vertical step. At the end of the vertical movement, series relay 104 deenergizes and transfers the operating circuit from the vertical to the rotary magnet.

When the calling subscriber operates his calling device in accordance with the second digit in the desired number, each of the resulting deenergizations of line relay 102 results in a circuit being closed for rotary magnet 111, the circuit of rotary magnet 111 at the first closure being as follows: from ground by way of armature 116 and its resting contact, armature 119 and its working contact, normally open off-normal contacts controlled by off-normal spring 118, armature 120 and its resting contact, resting contact of armature 125 and said armature, armature 131 and its resting contact, and rotary magnet 111 to battery. By the operation of the rotary magnet, the wipers of the switch are rotated into engagement with the set of contacts in the selected level in which the desired line terminates, which in this case is the set comprising contacts 136-138, inclusive. Relay 107 energizes in multiple with rotary magnet 111 and, being slow-acting, is maintained energized during the entire rotary movement. Upon energizing, relay 107 disconnects test wiper 134 from the upper winding of switching relay 108 and connects it to busy relay 106 at armature 126, and at armature 127 places a shunt around armature 125 and its resting contact so as to guard its own circuit and that of rotary magnet 111 from being opened prematurely by busy relay 106 in case that relay energizes due to test wiper 134 passing over busy test contacts.

Assuming the called line to be busy, test contact 137 is grounded, and busy relay 106 is accordingly energized when the switch wipers come to rest upon the desired set of contacts, and relay 107, upon deenergizing at the end of the rotary movement, completes a locking circuit for busy relay 106 as follows: from ground by way of the working contact of armature 118 and said armature, armature 124 and its working contact, and the normally closed contacts controlled by armature 126 to battery by way of busy relay 106. Also, since busy relay 106 is energized, slow relay 107, upon falling back, opens its own circuit and that of stepping magnet 111 from the impulsing circuit so as to prevent any further operation of the switch wipers, and any further operation of relay 107 in case the calling subscriber should again turn his calling device. Busy relay 106 at its lower armature connects a

lead from the busy signalling machine to the lower heavy talking conductor, thereby sending back the usual busy tone to the calling subscriber to inform him that he cannot obtain the desired connection for the time being. Upon hearing this tone, the calling subscriber replaces his receiver, whereupon the partly established connection is released in the usual manner.

Assuming now that the called line is idle when called as hereinbefore described, test contact 137 is not grounded and busy relay 106 is consequently not energized when the switch wipers come to rest on the terminals of the desired line, and slow-acting relay 107, upon deenergizing, completes a circuit for switching relay 108 in series with cut-off relay 139 of the called line circuit LC' at armature 126 as follows: from ground by way of the working contact of armature 118 and said armature, armature 124 and its resting contact, upper winding of switching relay 108, resting contact of armature 126 and said armature, test wiper 134, test contact 137, and cut-off relay 139 to battery. Upon energizing, cut-off relay 139 disconnects the normal battery and ground connections of the called line at its upper and lower armatures.

In the connector C, switching relay 108, upon energizing, first closes a locking circuit for itself at its lightly adjusted armature 130, and then places ground directly on test wiper 134 at armature 129; disconnects rotary magnet 111 and slow-acting relay 107 at armature 131; and at armatures 128 and 132 connects up the line wipers, whereupon ringing current is intermittently projected out over the called line to ring the bridged bell at the called substation.

When the called subscriber responds to the ringing of his bell by removing his receiver, a direct current circuit is closed over his line conductors for the upper winding of ring-cut-off relay 105 of the connector C. Ring-cut-off relay 105, upon energizing, first closes a locking circuit for itself at its lightly adjusted armature 122, and then disconnects the line wipers from its own upper winding and the source of ringing current and extends them to the windings of back-bridge relay 101. When this occurs, back-bridge relay 101 energizes over the called line, and reverses the incoming conductors 75 and 77 as regards their connection with the windings of line relay 102, thereby reversing the direction of current flow in the calling subscriber's loop. This operation does not have any particular function in the present case, but is used in other cases for operating meters and the like. The calling and called subscribers may now converse with each other as desired, the talking circuit being outlined by the heavy conductors.

When the conversation is terminated, the

two subscribers replace their receivers, and when the receiver is replaced at substation A', back-bridge relay 101 of the connector C deenergizes and reverses the current flow 5 in the calling line to normal.

When the receiver is replaced at the calling substation, the circuit of line relay 102 is opened. Upon deenergizing, line relay 102 opens the circuit of release relay 103 at 10 armature 116. Slow-acting release relay 103, upon deenergizing in response to the prolonged opening of its circuit at this time, removes ground from the upper terminal of the upper winding of switching relay 108 at 15 armature 118, removes ground from release trunk conductor 76 at armature 117, and at armature 119 closes a circuit for release magnet 109 by way of off-normal contacts 112. Upon the energization of release magnet 109, 20 the shaft and wipers of the connector C are restored to normal position in the usual manner, the circuit of release magnet 109 being opened at off-normal contacts 112 by the switch shaft when the latter reaches normal 25 position.

In the finder F, the removal of the ground potential from release trunk conductor 76 renders the finder F selectable to the finder allotter FA again and opens the circuit of 30 relay 95. Relay 95, upon deenergizing, removes ground from test wiper 73 at armature 97, and at armatures 96 and 98 disconnects its line wipers.

Cut-off relay 14 of the line circuit LC 35 now deenergizes in response to the opening of its circuit by relay 95 of the finder F; opens a point in its previously established locking circuit at armature 20; replaces ground on test contact 27 at armature 19; 40 and at armatures 18 and 21 connects up the calling bridge again.

It may happen occasionally that a calling subscriber makes a call, and start relays 42 and 43 energize to place ground on the start 45 conductor 99 through relay 44, but the starting circuit is open, for example, at armature 59 and its resting contact or at armature 89 and its resting contact. When this occurs, relay 44 is not energized and a 50 circuit is closed through armature 51 and its resting contact for the lamp L' to battery through the common pilot relay 49. Relay 49, upon energizing, closes a circuit for the alarm buzzer 50, thereby attracting the attention of an attendant who may take 55 such steps as he deems necessary to clear up the trouble.

It may happen occasionally that the chain circuit which shunts starting relay 42 is 60 opened and the circuit for starting relay 43 is not closed. This may happen due to the shunting chain circuit of relay 42 being opened accidentally due, for example, to dirty contacts, or it may happen, when the 65 chain circuit is opened in the usual manner

when a subscriber makes a call, on account of the fact that a contact such as armature 17 and its working contact is dirty or badly adjusted and, therefore, does not close the circuit of relay 43. However, regardless of 70 the cause for the above named condition existing, a finder is started in the usual manner in response to the grounding of the start conductor at armature 49, but, since relay 43 is deenergized, a circuit is closed through 75 armature 50 and its resting contact for relay 45. Upon energizing, relay 45 disconnects test contact 24 of a dead set comprising contacts 23-25, inclusive, from ground, and connects it to relay 46 through armature 54 80 and its resting contact.

It will be assumed now that the above named condition exists because a subscriber is making a call and the contact on his line relay fails to close the circuit of relay 43. 85 It will be assumed further that the finder allotted in this case is the finder F, and that the wipers of the finder F pass over the contacts 23-25, inclusive, before they come into engagement with the contacts of the calling 90 line. That being the case, when the wipers 72-74, inclusive, arrive on the contacts 23-25, inclusive, a circuit is closed for relay 46 of the relay group RG as follows: from ground by way of the working contact of 95 armature 49 and said armature, armature 50 and its resting contact, relay 46, resting contact of armature 54 and said armature, working contact of armature 52 and said armature, test contact 24, test wiper 73, armature 100 97 and its resting contact, wiper 92, working contact of armature 85 and said armature, wiper 91, and rotary magnet 94 to battery. Relay 46, upon energizing over this circuit, connects up the marginal relay 47 at armature 53 in multiple with rotary magnet 94. 105 Relay 47 does not energize in multiple with magnet 94 owing to its marginal adjustment, and to the reduction in potential due to the relative values of the resistances of relay 46 110 and stepping magnet 94. Test relay 84 in the finder allotter FA, Fig. 1, does not energize at this time in multiple with relay 46 of the relay group RG owing to its own stiff adjustment and to the relatively low 115 resistance of relay 46.

The resistance of relay 46 is of such a value that while it appreciably slows up the energization of stepping magnet 94 of the finder F, it does not prevent magnet 94 120 from energizing and, consequently, the wipers of the finder F are not stopped on the contacts 23-25, inclusive, but are rotated on in search of the calling line.

When wiper 73 passes off test contact 24, 125 the shunt of stepping magnet 94 is removed from around relay 47 in the relay group RG, whereupon relay 47 energizes in series with relay 46 through armature 53 and its working contact, and at armature 54 disconnects 130

test contact 24 from the junction of its own winding and that of relay 46, and connects it to the upper winding of relay 48 for a purpose which will be explained fully hereinafter.

When the finder F reaches the terminals of the calling line, the calling line relay de-energizes in the hereinbefore described manner and replaces the shunt around relay 42, 10 whereupon relay 42 deenergizes and opens the circuit of relays 45-47, inclusive. These relays then deenergize with results which are apparent.

It will be assumed now that the chain circuit which keeps relay 42 normally shunted has become open accidentally at a time when no line is calling; that a finder is started, the finder F, for example, in the usual manner; and that relays 46 and 47 are energized 20 as hereinbefore described in response to the wipers of the finder F passing over the set of contacts 23-25, inclusive. Under these conditions, no calling line is found and the wipers of the finder F continue to rotate 25 until they come into engagement with the contacts 23-25, inclusive, the second time. When this occurs, relay 48 is energized by means of its upper winding over a circuit which includes the working contact of armature 54 and said armature, and the previously traced circuit to battery including stepping magnet 94. The resistance of the upper winding of relay 48 is sufficiently high to prevent stepping magnet 94 from operating 30 in series with it, but is not high enough to allow the marginally adjusted switching relay 84 to energize in multiple with it. Upon energizing, relay 48 closes a locking circuit for itself at armature 56; opens a point in 35 the circuit of the signal lamp L' and prepares a circuit for the signal lamp L at armature 57; and at armature 59 opens the start conductor. When this occurs, line relay 82 of the finder allotter FA deenergizes; 40 disconnects test relay 84 at armature 86; and at armature 85 disconnects the junction of test relay 84 and stepping magnet 94 from test wiper 73 of the finder F, thereby 45 opening the circuit of the upper winding of relay 48, leaving relay 48 energized by means 50 of its lower winding.

In the relay group RG, as a result of the opening of the starting circuit at armature 59 of relay 48, relay 44 deenergizes and completes a circuit for the signal lamp L as follows: from ground by way of the working contact of armature 49 and said armature, armature 51 and its resting contact, armature 57 and its working contact, the lamp L, 55 and pilot relay 49 to battery. The lamp L now becomes lighted to inform the attendant of the nature of the trouble, and the pilot relay 49, upon energizing, closes a circuit for the buzzer 50 to attract the attention 60 of the attendant.

In case a call is made before the attendant has responded to the alarm, the equipment is not in any way tied up, and the finder F starts hunting for the calling line in the usual manner, for the reason that relay 43, 70 on energizing, when the call is made, opens the circuit of relays 45-48, inclusive, whereupon these relays deenergize and the start wire is connected up again at armature 59 and its resting contact. The finder F automatically steps off the contacts 23-25, inclusive, on account of the fact that relay 45 of the relay group RG, on deenergizing, grounds test contact 24 again at armature 52.

When the call is taken care of and the 80 finder allotter FA allots the next finder, the start conductor remains grounded owing to the fact that relay 42 is still unshunted and the allotted finder repeats the process described above with the result that the lamp 85 L is again lighted to inform the attendant of the trouble.

It will be seen from the foregoing description of the starting arrangement and of the trouble indicating signals that a very efficient starting arrangement has been provided; that the attendant is signalled in case the start wire itself is open; and that the attendant is signalled eventually in case the chain starting circuit is opened accidentally. 95

Perhaps in concluding it will be well to sum up certain parts of the foregoing description by stating that two start relays are provided instead of one as heretofore. One start relay has its circuit normally closed, 100 but is shunted by a chain circuit including normally closed contacts in series on all the line relays. This start relay can be depended upon absolutely to energize whenever a call is made. However, this relay sometimes 105 energizes due to an accidental opening of its shunting chain circuit and starts a finder when no line is calling. The arrangements above described are made for then stopping the finder to prevent excessive 110 wear. The first starting relay having been rendered ineffective, the second start relay comes into play to restart the finder when a call is actually made. This other starting relay, although perhaps not quite so reliable 115 as the normally shunted relay, is energized in a standard circuit, nevertheless, and affords an effective means of starting finders pending the repair of the trouble in the other starting circuit. 120

What is claimed is:

1. In a telephone system, telephone lines, a plurality of finders, a circuit for starting an idle one of said finders in search of a calling one of said lines, a signalling circuit, means for closing said circuits at the same time, and a relay in series with the starting circuit for opening the signalling circuit. 125

2. In a telephone system, a group of telephone lines, a line relay for each line, a plu- 130

rality of finders, a circuit for starting an idle one of said finders in search of a calling one of said lines, a pair of normally closed contacts and a pair of normally open contacts on each line relay, means for operating one of said line relays when the associated line is calling to open its normally closed contacts and to close its normally open contacts, and means for closing said starting circuit responsive to either the opening of said normally closed contacts or the closure of said normally open contacts.

3. In a finder system, a normally closed starting circuit, means responsive to any opening of said circuit for starting a finder, and means for stopping the started finder and signalling an attendant when said circuit is opened due to some cause other than the initiation of a call.

4. In a telephone system, telephone lines, a plurality of finder switches having wipers for finding the calling ones of said lines, an allotter for allotting said finders for use, a magnet in each of said finders for bringing about the movement of the associated wipers, a circuit for each magnet including a wiper of the associated finder, and a relay in said allotter for closing the circuits of said magnets.

5. In a telephone system, telephone lines, a plurality of finders for finding the calling ones of said lines, an allotter for allotting said finders for use, and a test relay in said allotter, a circuit for said relay over which it individually tests the lines searched over by an allotted finder.

6. In a telephone system, subscribers' lines, a group of finders for extending said lines when calling, magnets in said finders a test relay common to all of said finders, and means for associating said relay with said finders successively, a circuit for said relay including the magnet of said associated finder in series over which said relay is energized to control said magnet.

7. In a telephone system, subscribers' lines, a group of finders for extending said lines when calling, a test relay common to all of said finders, a test wiper for each finder, and means for connecting said test relay to said wipers in turn as the several finders are taken for use.

8. In a telephone system, subscribers' lines, a group of finders for extending said lines when calling, motor magnets in said finders a test relay common to all of said finders, an auxiliary switch for selecting idle finders one at a time and for connecting said test relays thereto in a circuit including said motor magnet, and means in said switch for restricting said test relay to the use of any finder selected.

9. In a telephone system, subscribers' lines, a group of finders for extending said lines when calling, motor magnets for said

finders, a common line relay and a common test relay for controlling all said motor magnets, and means for connecting said test relay in series with one of said magnets in a circuit controlled by said line relay thereby enabling said relays to control said magnets separately. 70

10. In a telephone system, subscribers' lines, a group of finders for extending said lines when calling, motor magnets for said finders, a common line relay, a common test relay, an auxiliary switch for associating said relays with said finders one at a time, said test relay being in series with the motor magnet of the selected finder, and circuits 75 for enabling said line relay to close the motor magnet circuit of any finder with which it is associated, and means subsequently controlled by said test relay for opening the circuit of said motor magnet. 80

11. In a telephone system, telephone lines, a plurality of finders, a circuit for starting an idle one of said finders in search of a calling one of said lines, a signal, means for closing said starting circuit at one point, 90 and means responsive to the closing of said circuit for operating said signal in case said starting circuit is open at another point, the last-named means including a relay in series with said starting circuit. 95

12. In a telephone system, subscribers' lines, a group of finders for extending said lines when calling, magnets in said finders, a test relay common to all said finders, a test wiper for each finder, and means for connecting said test relay to said wipers and said magnets as the several finders are taken for use. 100

13. In a telephone system, telephone lines, a group of finder switches having wipers, 105 a magnet in each switch, an allotter for allotting said finders for use, a test relay common to said finders, means responsive to the initiation of a call from one of said lines for connecting said test relay in a circuit including the motor magnet of the allotted finder, and means for shunting said relay and for completing an energizing circuit for said magnet which operates to drive said wipers in search of said calling line. 110

14. In a telephone system, a group of finders having wipers, telephone lines accessible to said wipers, motor magnets in said finders for driving said wipers, a test relay common to said finders, means for allotting said finders for use one at a time and for preparing a circuit for said test relay in series with said motor magnet, and means responsive to the initiation of the call by one of said lines for completing said circuit and for short circuiting said test relay until said wipers are associated with said calling line. 120

15. In a telephone system, a group of finders having wipers including a test wiper, 125

telephone lines terminating in contacts accessible to said wipers, motor magnets in said finders for driving said wipers, a test relay common to said finders, an allotter for allotting said finders for use one at a time and for preparing a circuit for said test relay in series with said motor magnet, means responsive to the initiation of a call by one of said lines for removing ground from an associated contact to mark that line calling, means for then completing said circuit to operate said magnet and for short circuiting said test relay through said test wiper, and means operated by the energization of said test relay when said test wiper finds said marked contact for controlling said finder.

16. In a finder system, a plurality of finders having banks of contacts over which

wipers are driven in search of a calling line, 20 a normally closed starting circuit for said finders, means responsive to any opening of said circuit for starting a finder, an arresting contact set in said bank, means responsive to the first engagement of said wipers 25 with said contact set for preparing a finder stop circuit, means responsive to a second engagement of said wipers with said contact set for completing said stop circuit to stop said finder wipers on said arresting 30 contacts, a signal, and means operated by the closure of said stop circuit for operating said signal.

In witness whereof, I hereunto subscribe my name this 20th day of December, A. D., 35 1922.

RUDOLPH F. STEHLIK
